UNITED STATES PATENT OFFICE.

JOHN F. METTEN, OF PHILADELPHIA, PENNSYLVANIA, ASSIGNOR TO THE WM. CRAMP & SONS SHIP & ENGINE BUILDING COMPANY, A CORPORATION OF PENNSYLVANIA.

STEAM-TURBINE.

1,080,573.

Specification of Letters Patent.

Patented Dec. 9, 1913.

Application filed February 19, 1909, Serial No. 478,820. Renewed November 9, 1912. Serial No. 730,493.

To all whom it may concern:

Be it known that I, JOHN F. METTEN, a citizen of the United States, residing at Philadelphia, in the county of Philadelphia and State of Pennsylvania, have invented 5 certain new and useful Improvements in Steam-Turbines, of which the following is a full, clear, and exact specification.

This invention relates to steam turbines, 10 and more particularly to improvements in the construction and mounting of the nozzles and diaphragms, whereby the nozzles may be removed without taking out the rotor or diaphragms, and whereby the weight 15 is reduced, and construction simplified.

Turbines as commonly constructed, have 20 a removable outer casing, but if it is desired to inspect or renew the nozzles, it has been necessary to remove the rotor, and in 25 some instances to disassemble the entire turbine. In order to enable the nozzles to be readily removable, I propose to provide the nozzles in a ring capable of being removed by sections independently of the rotor and 30 the diaphragms. As herein shown, the nozzles are formed in a ring which is divided into sections, preferably disposed so as to normally have their meeting edges along the line of the casing joint. The nozzle ring 35 encircles and engages the diaphragm which separates adjacent rotors, and is itself carried in the casing in such manner as to prevent movement when in operative position, but permitting one portion to be removed 40 through an opening in the casing, and the remainder to be slid around in the casing until it can be pulled out through the opening. In a modified construction the nozzle ring carries the stationary guide blading, 45 which is also removable with the nozzle ring sections. This construction is advantageous in assembling of the turbine, as will be more fully pointed out.

A further feature of the invention relates 50 to improved means for constructing and securing the diaphragms, whereby the cost of building is reduced, weight is saved, and a more compact arrangement made possible. According to this portion of the invention, 55 I construct a diaphragm of a dished plate, having at its center a reinforcing gland ring

and at its periphery a second reinforcing ring adapted to be engaged by the nozzle ring, which latter engages the casing. The diaphragm plate is preferably of steel and 55 the rings of wrought steel secured on opposite sides thereof to overlie one another and thereby save space, while the nozzle ring may be of cast iron.

The rotor or wheel consists of a hub fastened 60 to the shaft, and having a web portion, preferably composed of a single plate, having a widened blade carrying rim which overhangs the hub. The diaphragm nests partially within the overhanging rim of the 65 rotor on one side near its periphery, and the center of the diaphragm is adapted to nest within the overhanging hub of the rotor on the other side, without causing the rotors and diaphragm to strike each other. The 70 aggregate saving in overall length in a turbine having a number of stages, or rotors and diaphragms, will be very considerable, it being seen that such a reduction in overall length does not reduce the power, but 75 saves the extra weight of shaft, casing, etc., otherwise necessary.

Further objects and advantages will more fully appear in connection with the description of the accompanying drawings, 80 wherein—

Figure 1 is a vertical half section of one of the stages of a turbine, Fig. 2 is a transverse section of a turbine on the line 2—2 of Fig. 1, looking in the direction of an arrow, and Fig. 3 shows the modified nozzle ring construction.

1 represents the casing of the turbine, 2 the shaft extending through the casing, 3, 3, rotors separated by a diaphragm 4. Each 90 rotor 3 is built up of a hub 5, preferably a single intermediate plate 6, and an overhanging blade ring 7 having rows of blades 8 secured to its periphery, and in between these rows of blades project the stationary 95 guide blades 9 secured to the casing 1 or to the nozzle ring hereinafter described. By this construction, the difficulty of obtaining special steel castings for the whole rotor is avoided, and a rigid compact construction 100 is attained.

The diaphragm comprises a preferably

dished or concave steel plate 10, at the outer edge of which is secured a grooved steel ring 11, while at the opposite side on the inner edge of the plate 10 a steel gland ring 12 is secured thereto and carrying packing 13 bearing on the hubs of the rotors 3, 3. It will be seen that the rings 11 and 13 stiffen the disk or plate 10, thereby permitting it to be made considerably lighter without rendering it liable to distortion when subjected to pressure, and also that by dishing the plate and fastening the rings on opposite sides, they overlie one another and save space. The overhanging rim 7 of the rotor 15 forms a recess 25 into which the diaphragm extends, see Fig. 1, and the edges of the plate 10, ring 11, and nozzle ring segments 19 may be beveled as at 26 for this purpose, so that the outer edge 27 of the diaphragm 20 will be nested within and overhung by the adjacent edge of the blade ring rim 7. In like manner the opposite side of the diaphragm at the center is adapted to be, and is shown as, overhung by, and nesting 25 within the edge of the blade ring rim 7 of another rotor. It will thus be seen that the distance between successive rotors can be materially reduced by the diaphragm construction herein described, with a resultant 30 material decrease in the weight of the entire machine. This is a feature of importance in marine turbines, and especially for war vessels where minimum displacement of propelling machinery is desired, in order to 35 gain displacement for other uses, and to avoid penalties for over weights.

The diaphragm, or the ring 11 secured thereto, is provided with a peripheral groove 16, and also the casing 1 has a groove 17. 40 Mounted to slide between these grooves and at the same time lock the diaphragm against longitudinal movement is a nozzle ring 19, preferably of cast iron and containing nozzles 20 of any preferred configuration. The 45 nozzle ring segments may be secured to the casing by bolts 21, in order to resist the reaction of the flow through the nozzles. These bolts are exposed when the casing is lifted, the upper nozzle section coming off 50 with the casing, and the lower one being removable by sliding in the groove when the bolts are removed. As shown in Fig. 2, the nozzle ring 19 is divided into halves, which, when one half of the casing is 55 moved can be separated from between the casing and the diaphragm independently of the rotor, one by simply being lifted, and the other by being slid around the groove until it can likewise be lifted. It will thus 60 be seen that removing one section of the casing releases or unlocks one section of the nozzle ring, permitting its removal, and that the other section can then be pushed circumferentially so as to be likewise removed.

It will be understood that the ring may be 65 divided into a large number of smaller segments if desired, and also that less than half of the casing may be removed if it is desired only to take out the nozzle ring. Furthermore, as long as the nozzle ring is positioned 70 in the grooves between the casing and the diaphragm, the latter is locked against displacement lengthwise of the shaft, and in removing the ring from between, the diaphragm may turn with the ring or be used 75 to assist in pushing the ring out.

In Fig. 3, the nozzle ring sections 23 are made wider, and the grooves 7 in the casing correspondingly so, to contain an extension 24 of the ring having on its inner periphery 80 slots in which the stationary guide blades 8 are carried. The ring sections may be bolted to the casing in the same manner as before described. By this arrangement, besides providing for the removal of the guide 85 blades, the blading grooves need not be cut in the casing but can be made in the nozzle ring sections to better advantage.

From the foregoing description it will be seen that I have provided a built up peripherally overhanging rotor in combination with a construction of nozzle ring removable independently of the rotor, and permitting the use of a reinforced plate diaphragm adapted to be locked by the ring. By making the diaphragm of plate metal, considerable weight is saved and cost of material, and by dishing it, the requisite stiffness is secured. The cost of making the rings and securing them so as to reinforce the diaphragm is less than that of making the whole diaphragm of one or two pieces.

It will be understood that while a single diaphragm is shown and described herein, the invention contemplates the use of a number of diaphragms and nozzle rings similarly constructed, in connection with a suitable number of rotors, so that the aggregate saving in weight and cost and increased compactness will be considerable.

Modifications in the arrangement and specific construction of parts may be made without departing from the scope of the invention.

Having thus described my invention, I declare that what I claim as new and desire to secure by Letters Patent, is:—

1. The combination in a turbine with a rotor, a casing having a removable segment, and a dished diaphragm having a packing 120 around the axis of the rotor, of a separate nozzle carrying element, and means whereby the nozzle carrying element engages the casing and the diaphragm to lock the latter against longitudinal movement.

2. The combination with a turbine casing, a portion of which is removable, of a rotor therein, a diaphragm, and an element slid-

- ably removable from between the casing and the diaphragm and locking the diaphragm when in place.
3. The combination with a turbine casing, a portion of which is removable, of a rotor therein, a diaphragm, and a divided nozzle carrying ring slidably and removably mounted between the casing and the diaphragm.
- 10 4. The combination with a turbine casing, a portion of which is removable, of a rotor, a diaphragm, and a nozzle carrying ring slidably interlocking with both the casing and the diaphragm whereby the nozzle ring holds the diaphragm against displacement.
5. The combination with a turbine casing, a portion of which is removable, said casing having a groove around its inner surface, of a rotor, a diaphragm, and a segmental nozzle ring formed to slidably interlock with the diaphragm and the casing, whereby to hold the diaphragm in position and to be removable independently of the rotor or the diaphragm.
- 25 6. In a turbine, the combination with a casing having a removable section, a diaphragm and a rotor, of a segmental ring slidably interlocking the casing and the diaphragm whereby a segment within the casing can be pushed around and removed through an open portion of the casing.
7. A diaphragm for an elastic fluid turbine comprising a plate, a separate nozzle ring segment interlocking therewith on its periphery, and a gland ring secured to said plate at its interior edge.
- 35 8. A diaphragm for an elastic fluid turbine comprising a disk, a ring secured to its periphery, a separate nozzle ring segment interlocking therewith, and a gland ring secured to said plate at its interior edge, said plate being dished and the rings secured thereto being on opposite sides thereof.
- 40 9. A diaphragm for an elastic fluid turbine comprising an intermediate plate section, a nozzle ring support secured to the outer edge of said plate, a separable nozzle ring segment interlocking with the aforesaid ring, and a gland ring secured to said plate at the inner edge thereof.
- 50 10. The combination with a divided casing, of a rotor, a continuous diaphragm between the rotor shaft and the casing, and a removable nozzle ring segment between the casing and the diaphragm, said ring being capable of removal without removing the diaphragm.
- 55 11. The combination with a turbine casing having a removable segment, of a rotor therein, a segmental nozzle ring encircling the rotor, and means whereby the ring is held when the casing is closed, but can be removed independently of the rotor when the casing is open.
12. In an elastic fluid turbine, the combination with a casing, of a shaft therein, and a diaphragm encircling said shaft, said casing being divided on a longitudinal plane through the shaft, a nozzle ring separable from the diaphragm and separably fitted to the casing, and removable fastenings for securing the nozzle ring sections to the casing sections. 65
13. In an elastic fluid turbine, the combination with a casing, of a shaft therein, and a diaphragm encircling said shaft, said casing being divided on a longitudinal plane through the shaft, said diaphragm comprising a nozzle ring divided into a plurality of segments and slidably interlocking with the casing and the diaphragm. 70
14. A diaphragm for an elastic fluid turbine comprising a plate, a ring secured to its periphery, and an inner ring secured to the middle portion of said plate. 75
15. A diaphragm for an elastic fluid turbine comprising a plate, a ring secured to its periphery, and an inner ring secured to the middle portion of said plate, said rings overlying one another. 80
16. A diaphragm for an elastic fluid turbine comprising a dished plate, a ring secured to its periphery, and an inner ring secured to the middle portion of said plate. 85
17. A diaphragm for an elastic fluid turbine comprising a dished plate, a ring secured to its periphery, and an inner ring secured to the middle portion of said plate, said rings overlying one another. 90
18. A turbine comprising a sectional casing and a sectional nozzle ring having one section fastened to and removable with a casing section, and another nozzle ring section slidably removable independently of the remainder of the casing and the diaphragm. 95
19. In an elastic fluid turbine, the combination with a sectional casing of a sectional nozzle ring, and means for securing one nozzle ring section to the casing so as to be removable therewith, the other nozzle section being removable independently of the rotor and casing. 100
20. In a turbine, a casing, a built up diaphragm comprising a hub provided with a gland, a dished disk carried by said hub, and a blade carrying ring segment removably interposed between said disk and the casing. 115
21. In a turbine, the combination with a rotor having an overhanging blade carrying rim, of a diaphragm comprising a dished plate, a ring secured to its periphery, said diaphragm projecting within said overhanging rim, and an inner ring secured to the middle portion of the opposite side of said plate. 120
22. In a turbine, the combination with a

4
plurality of separated plate rotors each having an overhanging blade carrying rim, of a diaphragm interposed between said rotors comprising a dished plate having a ring secured to its periphery, the diaphragm projecting within the overhanging rim of one of said rotors, and an inner ring secured to the middle portion of the opposite side of

said plate, the diaphragm being adapted to project within the rim of said other rotor. 10

In testimony whereof I affix my signature, in presence of two witnesses.
